UNITED STATES PATENT OFFICE.

DENIS FLANAGAN, OF ACCRINGTON, ENGLAND

TWO-REEL SEWING-MACHINE.

1,201,570.

Specification of Letters Patent. Patented Oct. 17, 1916.

Application filed December 31, 1914. Serial No. 879,890.

To all whom it may concern:

Be it known that I, DENIS FLANAGAN, subject of the King of Great Britain and Ireland, and resident of Accrington, in the 5 county of Lancaster, England, have invented certain new and useful Improvements in Two-Reel Sewing-Machines, of which the following is a specification.

My invention relates to improvements in 10 two-reel sewing machines, the object being to provide means for passing the needle thread around the case containing the lower reel; said means being also designed to allow of the shortest thread loop possible 15 being made consistent with the size of the case containing the reel.

Prior to the date of my invention it has been proposed to employ in two-reel sewing machines a hook lever for the needle thread 20 having its pivoted point near the center of its length on a revolving disk or arm, the forward end of the lever carrying a hook for engaging the needle thread while the rear end is provided with a pin passing into 25 a slot formed in a fixed bracket carried by the bed plate of the machine. The aforesaid lever is pivoted at the outer end of the machine and operates transversely of it.

This invention consists in the novel construction and combination of the parts 30 hereinafter fully described and claimed.

My invention will be fully described with reference to the accompanying drawing in which—

35 Figure 1 is a front elevation, partly in section, of so much of a two-reel sewing machine as is necessary to show the application of my invention thereto, Fig. 2 elevation of same, partly in section, from the left 40 hand end, Fig. 3 plan, partly in section, Fig. 4 end elevation to an enlarged scale of the improved arrangement of hook showing the reel case in broken lines, Fig. 5 broken line front elevation of the reel case showing in 45 full lines some of the main features of my invention adjacent thereto and Fig. 6 plan of the hook and adjacent part.

Referring to the drawings the reel case *a* containing the lower reel is supported in its 50 holder *b* beneath the machine bed plate *c* with its axis parallel to the edges of said plate and with its pointed end *d* facing outward from the open end of the machine arm *e*. The case *a* and its holder *b* are of substantially ordinary construction. To pass the needle thread loop *f* around the reel case

I arrange beneath the bed plate *c* at one side of the machine a lever or arm *g*, the rear end of which is coupled to a crank *h* which may be driven in any suitable way as by bevel gear *i* from the usual operating shaft *j* of the machine. The forward end of this lever is provided with an improved hook *k* for engaging with the needle thread *f*. This hook is pointed at its forward end *m* to enable it to enter the needle thread loop, the shape being substantially as shown in Figs. 60

5 and 6. The shank of the hook projects laterally from the lever *g*, and its free end portion *m* projects forwardly from the free 65 end of the shank and is arranged parallel to the lever *g*. At the rear of the point it is provided with a T-shaped slot *n* running transversely of the hook to form the eye for the thread. The leg of the slot opens out at the 70

lower side of the hook, as will be seen from Fig. 5. Intermediate of the two ends, the shank of the hook projects laterally from the lever *g*, and its free end portion *m* projects forwardly from the free 75 end of the shank and is arranged parallel to the lever *g*. At the rear of the point it is provided with a T-shaped slot *n* running transversely of the hook to form the eye for the thread. The leg of the slot opens out at the 80

lower side of the hook, as will be seen from Fig. 5. Intermediate of the two ends, the shank of the hook projects laterally from the lever *g*, and its free end portion *m* projects forwardly from the free 85 end of the shank and is arranged parallel to the lever *g*. At the rear of the point it is provided with a T-shaped slot *n* running transversely of the hook to form the eye for the thread. The leg of the slot opens out at the 90

lower side of the hook, as will be seen from Fig. 5. Intermediate of the two ends, the shank of the hook projects laterally from the lever *g*, and its free end portion *m* projects forwardly from the free 95 end of the shank and is arranged parallel to the lever *g*. At the rear of the point it is provided with a T-shaped slot *n* running transversely of the hook to form the eye for the thread. The leg of the slot opens out at the 100

lower side of the hook, as will be seen from Fig. 5. Intermediate of the two ends, the shank of the hook projects laterally from the lever *g*, and its free end portion *m* projects forwardly from the free 105 end of the shank and is arranged parallel to the lever *g*. At the rear of the point it is provided with a T-shaped slot *n* running transversely of the hook to form the eye for the thread. The leg of the slot opens out at the 110

lower side of the hook, as will be seen from Fig. 5. Intermediate of the two ends, the shank of the hook projects laterally from the lever *g*, and its free end portion *m* projects forwardly from the free 115 end of the shank and is arranged parallel to the lever *g*. At the rear of the point it is provided with a T-shaped slot *n* running transversely of the hook to form the eye for the thread. The leg of the slot opens out at the 120

projections lie across the path of the hook in a stationary position, usually, though not necessarily, forming part of or being attached to the reel case holder.

5 The manner of engaging and disengaging the needle thread with the hook is as follows:—As the hook *k* passes over the top of the reel case *a* its pointed end penetrates and passes the loop of the needle thread *f* 10 into the T-shaped eye *n*. The forward motion of the hook causes the thread to pass against the rear end of the top portion of the eye. This formation of the T-shaped eye prevents the thread from slipping out 15 of the eye while the eye is being moved forwardly as well as while it is being moved backwardly. When the hook passes the forward end of the reel case and commences to recede the thread is drawn to the forward 20 end of the top portion of the eye as in Fig. 5, where it is retained during part of the upward motion of the hook behind the reel case. The hook then takes the thread between the curved projections *r* the latter 25 pushing the thread back slightly to a position opposite the open part of the eye. By a further upward movement of the hook and the slight momentary retardation of the thread due to its contact with the projections *r*, the hook is disengaged from the 30 thread which is then drawn up through the space *t* behind the projections *r* by the usual take-up mechanism and so tightens the stitch. The gear *i j* is a two-to-one gear and 35 causes hook *k* to complete its movement twice for each descent of the needle so that the hook *k* engages with the needle thread on each alternate movement only as will be understood.

40 Instead of a slidable block *o*, any other approved means for pivotally supporting the lever *g* may be provided which will permit the lever to move longitudinally so that the hook may move in an elliptical path.

45 What I claim is:

1. The combination, with a reel case, and a reel mounted therein; of a lever arranged parallel to the axis of the reel and to the rear of the reel case, means for pivotally 50 supporting the lever and permitting it to slide longitudinally, and a hook having a shank which projects laterally from the

front end portion of the lever and which terminates in a forwardly projecting end portion having a pointed end and a T-shaped 55 slot or eye for the thread provided with an opening on its lower side, the horizontal upper portion of the eye normally operating to prevent the disengagement of the thread while the lever is moving longitudinally in 60 each direction.

2. The combination, with a reel case, and a reel mounted therein; of a lever arranged parallel to the axis of the reel and to the rear of the reel case, means for pivotally 65 supporting the lever and permitting it to slide longitudinally, a hook having a shank which projects laterally from the front end portion of the lever and which terminates in a forwardly projecting end portion having a pointed end and a T-shaped slot or eye for the thread provided with an opening on its lower side, the horizontal upper portion of the eye normally operating to prevent the disengagement of the thread while 70 the lever is moving longitudinally in each direction, and two stationary curved projections arranged at the rear of the reel case and forming a passage for the front end portion of the hook and operating to disengage the thread from its said eye.

3. The combination, with a reel case, a reel mounted therein, and a stationary guide arranged parallel to the axis of the reel; of a block slidable longitudinally in the said 85 guide, a lever having its middle part pivoted to the said block and arranged to one side of the reel case, a hook having a shank which projects laterally from the front end portion of lever toward the reel case and 90 which terminates in a forwardly projecting end portion arranged parallel to the axis of the reel case and having a pointed end and a T-shaped slot or eye for the thread provided with an opening on its lower side, and 95 a revolute crank operatively connected to the rear end portion of the lever.

In testimony whereof I have hereunto set my hand in the presence of two witnesses.

DENIS FLANAGAN.
